UNITED STATES PATENT OFFICE

148,466

DESIGN FOR A BUILDING

James L. Gordon, Amarillo, Tex.

Application July 22, 1946, Serial No. 131,788

Term of patent 14 years

(Cl. D13—1)

To all whom it may concern:

Be it known that I, James L. Gordon, a citizen of the United States, residing at Amarillo, in the county of Potter and State of Texas, have invented a new, original, and ornamental Design for a Building, of which the following is a specification, reference being had to the accompanying drawing, forming part thereof.

Figure 1 is a front perspective view of a building, showing my new design.

Figure 2 is a side perspective view thereof, taken from the right side of Figure 1 and also showing the rear wall.

The left side of the building (not shown) is the same as the side shown in Figures 1 and 2.

I claim:

The ornamental design for a building, as shown and described.

JAMES L. GORDON.
